UNITED STATES PATENT OFFICE.

OSCAR L. PIERSALL, OF INDIANAPOLIS, INDIANA, ASSIGNOR OF ONE-HALF TO J. RICHARD FRANCIS, OF FLINT, MICHIGAN, AND ONE-HALF TO UNITED MACHINE COMPANY, OF INDIANAPOLIS, INDIANA, A CORPORATION.

SPARK INTENSIFIER.

Application filed April 15, 1922. Serial No. 553,125.

To all whom it may concern:

Be it known that I, OSCAR L. PIERSALL, a citizen of the United States, and a resident of Indianapolis, county of Marion, and 5 State of Indiana, have invented a certain new and useful Spark Intensifier; and I do hereby declare that the following is a full, clear, and exact description thereof, reference being had to the accompanying drawings, in which like numerals refer to like parts.

This invention relates to a spark intensifier.

The chief object of this invention is to 15 construct a spark intensifier of a minimum number of parts consistent with the function performed by said intensifier.

The chief feature of the invention is to 20 construct an intensifier of but a minimum number of parts which are so associated together that short circuiting of the terminals is prevented, and observation of the gap or spark is permitted whenever desired and protection is afforded at all other times.

25 The full nature of the invention will be understood from the accompanying drawings and the following description and claims.

In the drawings, Fig. 1 is a side elevational view of the invention showing the same in the normal position, or protective position. Fig. 2 is a side elevational view taken at right angles to Fig. 1. Fig. 3 is a side elevational view similar to Fig. 1, but 35 shows said parts in the observation position. Fig. 4 is a longitudinal sectional view taken on the line 4—4 of Fig. 2 and in the direction of the arrows. Fig. 5 is a transverse sectional view taken on the line 5—5 40 of Fig. 1 and in the direction of the arrows.

In the drawings 10 indicates a dielectric or insulation body, which herein is illustrated as cylindrical in form and provided with an axially aligned threaded opening 11 which extends through the body portion. Substantially intermediate the length of the body portion 10, there is formed a transverse opening 12, and said transverse opening herein extends completely through the body portion and communicates with the axial opening 11. Extending into the space at the junction of the two rectangularly positioned openings 11 and 12 is a pair of terminals 13 which are threaded and have

a threaded engagement with the opening 11 similarly formed, so that said electrodes or terminals 13 may be screwed into or retracted from the position shown in Fig. 4 by engaging the screw head 14 and turning the same. Each of the terminals or electrodes 13 supports a split or spring washer 15, and a nut 16 upon the terminal 13 locks the terminal in the adjusted position in the opening 11. Thus the two electrodes or terminals are secured in aligned and adjusted position.

The body portion 10 is herein shown as provided with a transversely extending opening 17, and said transversely extending opening 17 is herein shown, see Fig. 5, as 70 positioned at right angles to the axially aligned opening 11 and the transverse opening 12. The opening 17, however, does not extend completely through the body portion. Said opening 17 is adapted to receive 75 an intermediate or transverse cross wire or electrode 18. The essential elements of the spark intensifier have thus been described.

The connection from the usual spark coil is secured to one of the terminals 13, and 80 preferably the upper one, by means of the split washer 19 and locking nut 20. A strap 21 is apertured at 22 for engagement with the usual spark plug, and said strap 21 is also apertured at 23 to receive the other or 85 lower terminal 13. A locking washer 24 and a locking nut 25 secure the intensifier to the supporting strap 21, as shown in the several figures.

Another feature of the invention consists 90 in the provision of a closure for the opening 12. The opening 12, if desired, may terminate short of extending entirely through the body portion 10, and when so formed any simple closure may be positioned upon the 95 body portion 10 adjacent the opening 12, and said closure may be pivoted above the opening, thereby being manually movable from the closing or protecting position into the observation position. Thus, the spark 100 gap and the spark may be observed when the closure is moved out of registration with the opening 12. A dark background, therefore, is provided behind the sparking terminals, which makes them more prominent. 105 Herein, however, a neater and simpler construction is provided for the same purpose but which operates in substantially the same

manner. Such means is illustrated as a non-conducting or insulating shell or sleeve 26, which shell or sleeve is provided with an opening 27. The sleeve 26 is preferably mounted for arcuate movement upon the cylindrical body portion 10, so that the opening 27 is adapted to register with the opening 12, thereby permitting the terminals and spark to be observed. Herein the pin 18 is extended as shown clearly in Figs. 4 and 5, and said extended portion of the pin is seatable in a slot 28, the limits of the slot limiting the movement of the shell or sleeve in the open and closed positions. Herein, see Figs. 1 and 2, the opening 27 and the slot 28 are shown positioned such that rotational movement of the sleeve 26 also moves the sleeve longitudinally of the body portion and moves the opening 27 into registration with the opening 12. The slot 28, as shown clearly in Fig. 2, is inclined for the foregoing purpose. Said inclination is such that although the sleeve 26 may be manually turned and simultaneously elevated until the opening 27 registers with the opening 12, as shown in Fig. 3, the sleeve 26 will be automatically returned by gravity when released from manual engagement. This movement is assisted by the vibration of the engine.

It will be observed that although the opening 12 is extended entirely through the body portion, the sleeve 26, as shown in Fig. 5, forms a back wall for the opening 12, and, therefore, forms a dark chamber which permits the terminals and the spark to be more readily observed. As shown clearly in Fig. 3, the sleeve is movable longitudinally of the body portion as well as rotatable thereof. With the foregoing construction the danger of short circuiting, due to terminal caps or the like engaging portions of

the engine or other metallic members, is substantially eliminated, since any metallic member or engine although engaging one of the terminals 13 will engage the sleeve or body 10 and be prevented from engaging the other terminal 13.

The invention claimed is:

1. A spark intensifier including a body portion provided with two communicating openings, one of said openings extending entirely through the body portion, a pair of electrodes, each positioned in a portion of the extended opening and terminating within the body portion adjacent the communication with said other opening, and manually operable pivotally mounted closure means for exposing said other opening when turned and automatically returnable by gravity and the like upon the release from manual engagement in closing position.

2. A spark intensifier including a body portion provided with two communicating openings, one of said openings extending entirely through the body portion, a pair of electrodes each positioned in a portion of the extended opening and terminating within the body portion adjacent the communication with said other opening, a sleeve surrounding said body portion and having an opening therein adapted to register with the other opening, and a third electrode positioned between said first-mentioned electrodes and projecting outwardly beyond the body portion, said body portion including an inclined slot for receiving said projecting end of the third electrode for limiting movement thereof and for insuring automatic closure of the body opening when the sleeve is released.

In witness whereof, I have hereunto affixed my signature.

OSCAR L. PIERSALL.
